UNITED STATES PATENT OFFICE.

ELMER JACOBS, OF ALBION, AND WILBERT WARRING VAN SLYKE, OF DETROIT,
MICHIGAN.

SPRING-CUSHION OR THE LIKE.

1,182,276.

Specification of Letters Patent.

Patented May 9, 1916.

Application filed February 1, 1915. Serial No. 5,458.

To all whom it may concern:

Be it known that we, ELMER JACOBS and WILBERT WARRING VAN SLYKE, citizens of the United States, and residents, respectively, of Albion and of the city of Detroit, both in the State of Michigan, United States of America, have invented certain new and useful Improvements in Spring-Cushions or the like, of which the following

10 is the specification.

Our invention relates to improvements in cushions and more particularly to the means for fastening the facing at the bottom side of the cushion and also to the means for 15 fastening the bottom covering material, in the case of a closed bottom cushion, and the object of the present invention is to provide a fastening device for this purpose in which no sewing is necessary and in which the operation of fastening may be rapidly performed.

A further object is to provide a fastening device which will enable a uniform tension to be maintained at all points in the facing 25 material.

A further object is to provide a fastening device by which the bottom covering material is subjected to no tension and in which it is impossible for the facing material or 30 bottom covering material to become displaced over the edges of the cushion and a still further object is to provide protecting means for the facing material and bottom covering material at the bottom edges of the 35 cushion.

Our invention consists of a cushion frame having pointed prongs suitably spaced and carried at the bottom edges of the frame, and a supplemental frame engaged by the 40 said prongs, all as hereinafter more particularly described and illustrated in the accompanying drawings, in which:—

Figure 1, is a perspective view of one corner of a cushion, bottom side up, with 45 clamps carrying the prongs according to our invention and showing part of the facing material cut away. Fig. 2, is a perspective view of a supplemental frame which is adapted to engage the inside faces of the 50 prongs in Fig. 1. Fig. 3, is a perspective view of a modification of our invention in which a continuous frame is used to carry the prongs in place of the separate clamps shown in Fig. 1. Fig. 4, is a cross section 55 of the method of fastening in the case of

an open bottom cushion. Fig. 5, is a cross section of the method of fastening in the case of a closed bottom cushion.

Like characters of reference indicate corresponding parts in the different views. 60

1, are the springs of the cushion.

2, is the point at which the top edge of the facing is fastened.

3, is the facing material.

4, is a continuous angular frame which 65 extends around the bottom outside edges of the springs and which is suitably attached to the springs.

5, are pointed prongs extending perpendicularly outward from the said frame. 70

6, is a supplemental frame adapted to engage the inside faces of the prongs 5.

7, is the bottom covering material.

8, is a sheet of cardboard or other suitable material which covers the lower side of 75 the springs.

9, is the border wire surrounding the springs of the cushion and to which the same are fastened.

10, is a clamp which is fastened to the 80 border wire and the spring and carries one or more of the prongs 5, thereon.

The method of constructing a cushion employing our invention is as follows:—The springs are made in the usual way and the 85 clamps 10, carrying the prongs 5, are built into the springs. The upholstering of the top is done as usual and the top edge of the facing is attached along the edge 2. The facing is then pulled to the desired tension 90 and pressed down over the pointed prongs 5, so that the same penetrate the facing material. The supplemental frame 6, is then laid in place outside the facing material and inside the prongs which are then bent over 95 this frame as shown in Figs. 4, and 5, which holds the facing firmly in place.

In the modification of our invention in which the continuous angular frame 4, is employed the procedure is exactly as described above except that in making the springs this frame is built into them instead of the clamps 10.

In the foregoing we have described our invention as applied to an open bottom cushion but it is to be pointed out that it is equally applicable to a closed bottom cushion. In applying it to a closed bottom cushion the only change in the procedure is that a strip of cardboard or other suitable mate- 110

rial is placed over the bottom of the springs and after the facing material is in place and the prongs have penetrated it the bottom covering material is then turned over on itself to form a double thickness as at 11, and is then pressed down over the prongs 5, which are then displaced over the supplemental frame 6, holding both the facing material and the bottom covering material firmly in place. Our invention as applied to a closed bottom cushion is clearly shown in Fig. 5.

Hitherto cushions have been so constructed that the facing and bottom covering were sewed by hand. In this method it was very difficult to obtain a uniform tension in the facing material as any variation in the cutting of the same could not be taken up. In our method a perfect uniformity of tension can be obtained as it is only a case of properly adjusting the facing when penetrating it by the prongs.

Our invention is of great advantage in the case of closed bottom cushions both due to a great saving in time of manufacture and also in producing a much superior article. In former types of closed bottom cushions the facing and bottom covering material are sewed together. In this method, the facing and bottom covering material are as one continuous piece and both are under tension due to the action of the springs, and of course as a result the stitching at the connection is also under tension and in case of one stitch breaking the whole cushion goes. A further disadvantage of this old method of fastening is that the facing and bottom covering material are free to slide over the edges of the cushion and as a result, particularly in cushions having very deep springs these materials are soon displaced and the cushion loses its proper form.

Another disadvantage of these types of cushions which is completely overcome by our invention, is that there is no protection provided at the bottom side of the cushion against wear due to the sliding about of the cushion of the seat.

All the foregoing faults are overcome by

our invention as there is no sewing of the facing or bottom covering material at the bottom connection of the same but the two materials are entirely separate and absolutely no tension is carried by the bottom covering. Furthermore no sliding or displacement of the materials can occur as they are fastened firmly along the bottom edges of the cushion frame. In our method the cushion is much more durable, as there is protecting means provided at the bottom outside the facing and bottom covering which means rests on the seat and prevents any wear on the cushion due to the same sliding about. If desired a corded welt may be made at the outside edge of the bottom covering by simply inserting the cord between the layers of the same when it is bent back on itself.

Many modifications may be made in our invention without departing from the spirit of the same or the scope of the claim and the forms shown are to be taken as illustrative and not in a limiting sense and our invention is desired to cover any method of making cushions in which this principle of fastening is employed and is to be applied to either open or closed bottom types.

What we claim as our invention is:—

In a spring cushion or the like, the combination with the bottom edge border wire frame and the facing material extending around and underneath the same, and the springs and the outer supplemental border frame of less diameter than the inner border frame, so that it extends laterally inside of the same all the way around, of a plate connecting the springs with the inner border frame and formed with prongs which extend inwardly and downwardly through openings in the facing material to the bottom of the supplemental border frame around which they are clenched.

ELMER JACOBS.

WILBERT WARRING VAN SLYKE.
